2,483,497

ACTUATING DEVICE FOR EGG BEATERS

Theodore Keith Lewis, Wauneta, Nebr.

Application June 27, 1947, Serial No. 757,623

2 Claims. (Cl. 74—95)

1

This invention relates to an egg beater, and more particularly to the type operable by up-and-down motion of one hand.

A preferred embodiment of the invention is illustrated in the accompanying drawings.

Figure 1 is a vertical section through the new and improved egg beater.

Figure 2 is a fragmentary section similar to Figure 1, showing the egg beater in its lowermost position.

Figure 3 is a vertical section through the device, taken at right angles to the showing of Figure 7.

Figure 4 is a horizontal section, taken along the line 4—4 of Figure 3.

Figure 5 and Figure 6 are horizontal details.

The device comprises a tubular vertical casing 10 provided with an upper knob portion 11 that is shaped to be grasped by the palm of the hand to operate the casing 10 up and down. Centrally mounted in the casing 10 is a stationary vertical frame 12, in which are mounted at the top and bottom thereof two horizontal pins 13 and 14. The shaft 13 carries a pulley 15, and the lower shaft 14 carries a similar pulley 16. A flexible endless cable 18 is trained over both of the pulleys 15 and 16. The tension of the cable 18 is such that rotation of one of the pulleys 15 and 16 will serve to rotate the other. The lower pulley 16 has fixed thereto a vertical bevel gear 20, that is adapted to mesh with a horizontal bevel gear 21 to rotate a vertical shaft 22 secured to the horizontal bevel gear 21. A series of curved blades 23 is attached to the shaft 22, and these blades 23 are adapted to beat the egg in a suitable container. The bottom of the shaft 22 has a ball-and-socket connection with a suction cup 24 that is attachable to the bottom of the container, so that the shaft 22 may rotate freely with respect to the suction cup 24. If desired, the shaft 22 may rotate about an inner fixed shaft, which inner fixed shaft will itself be fixedly secured to the suction cup 24.

The flexible cable 18 has a lateral offset tab extending therefrom, this tab 26 being either integral with the cable 18 or fixed thereto by means of a set screw 27. This tab 26 is adapted to be held in an appropriate horizontal slot 28 in the casing 10, so as to be movable therewith. It is obvious, therefore, that as the casing 10 is moved vertically up and down, the tab 26 will move therewith, and the cable 18 will be rotated about the pulleys 15 and 16. The stationary frame 12 is provided at its lower portion with a stop 30, the stop 30 being apertured to permit movement

therethrough of the cable 18. This stop 30 is so positioned with respect to the frame 12 that the tab 26 will abut the upper surface of the stop 30 at the lowermost position of the casing 10 with respect to the frame 12. The upper portion of the frame 12 on the side opposite the stop 30 is provided with another stop 31, this stop 31 being likewise apertured to permit movement therethrough of the cable 18. Another tab 33, fixed laterally to the cable 18 by means of a set screw 34, is adapted to bear on the upper surface of the stop 31 when the casing 10 is in its uppermost position with respect to the frame 12.

The casing 10 is connected to the frame 12 by means of three telescoping members 40, 41, and 42, that are slidable with respect to one another and with respect to the upper portion of the frame 12. The upper telescoping member 40 has a button 43 that is embedded in the knob 11, so as to be fixed thereto. The upper portion of the frame 12 has a central recess 44 to contain the telescoping members 40, 41, and 42 when they are in compacted position. A coil spring 45 bears against the bottom of the recess 44 and against the bottom of the telescoping member 40, to normally urge the telescoping members 40, 41, and 42 into expanded position.

In the operation of the device, the knob 11 is depressed, telescoping the members 40, 41, and 42 against the action of the coil spring 45. As the casing 10 goes down, the tab 26 attached to the cable 18 also goes down, and the cable 18 is given a counter-clockwise movement, as seen in Figures 1 and 2. The casing 10 continues its downward movement until the tab 26 abuts the upper surface of the stop 30. When the hand is released from the knob 11, the coil spring 45 will restore the casing 10 to its upmost position, and the upper limit of this position will be determined by the engagement of the tab 33 attached to the cable 18 as it abuts the upper surface of the upper stop 31. During both the downward movement and the upward movement of the casing 10, the shaft 22 will be rotated about a vertical axis, thereby actuating the beating blades 23.

I claim:

1. Actuating mechanism for an egg beater comprising a frame, two pulleys rotatably mounted on said frame in vertical alignment, an endless flexible belt drivably trained over said pulleys, a hollow handle substantially cylindrical in shape mounted over said frame, a telescoping spring biased means connecting said handle to said frame, a tab secured to said belt adapted to be engaged by said handle for vertical movement

therewith, and gear means associated with one of said pulleys for driving the egg beater.

2. A mechanism for turning the shaft of an egg beater comprising a frame having a bearing for said shaft, a mitre gear secured on said shaft, a second mitre gear rotatably mounted on said frame, a pulley secured to said second mitre gear, a second pulley rotatably mounted on said shaft in vertical alignment over said first pulley, an endless flexible belt trained over said pulleys, a hollow handle having one end thereof closed, said handle enclosing one end of said frame, a compression spring axially mounted within said handle between the closed end thereof and said

5

10

frame end, and drive means secured to said belt engageable with said handle whereby turning motion is imparted to said egg beater shaft by an up-and-down movement of the handle.
